HIGH POWER TUBE STRUCTURE

Ilia E. Mouromtseff, Wilkinsburg, Pa., and Henry N. Kozanowski, Collingswood, N. J., assignors to Westinghouse Electric & Manufacturing Company, East Pittsburgh, Pa., a corporation of Pennsylvania

Application February 20, 1936, Serial No. 64,858

6 Claims. (Cl. 250—27.5)

Our invention relates to electron discharge devices and especially to high power vacuum tube devices.

It is an object of our invention to provide a vacuum tube that will operate satisfactorily with high voltage and power inputs necessary for certain modern day installations.

In response to the demand for increased power from high power tubes, it has been the practice to make sturdier the elements of these tubes and to apply the increased values of power and voltage to the tubes. It has been found that tube structure that operated satisfactorily at lower power and voltage ratings failed to perform satisfactorily at these increased ratings. First, at certain spots local boiling would occur inside the water jacket. We have made a careful analysis of this phenomenon and have discovered the boiling is caused by non-uniform distribution of electronic flow along the active portion of the tube particularly in the vicinity of cut-off bias point. This reduces the permissible plate dissipation for the tube.

In addition, at high operating plate and grid voltages, particularly in modulated class C operation, flash-overs may occur within the tube. The main cause of this phenomenon is a concentrated cold discharge between the tube electrodes due to the existence of sharp points, contamination and absorbed gas molecules.

The modifications will be apparent from the following description and the drawing, in which:

Figure 1 is a cross section through a preferred arrangement of the vacuum tube with certain parts in elevation.

Fig. 2 is a cross section at right angles to the view in Fig. 1 with certain parts in elevation, and

Fig. 3 is a cross section on lines III—III of Fig. 2.

In the drawing, we have illustrated the high vacuum type of tube with the exterior anode 10 sealed to the glass insulating portion 11, as is well known in the art. The glass insulating portion 11 supports the familiar reentrant stem 12 having the cathode leads 13, 14 sealed therethrough. The grid lead 15 likewise is sealed through a portion of the glass insulation 11 and is connected to the grid structure comprised of sturdy supporting rods 16 extending longitudinally of the tube 10 and supported from the press 12 in any convenient manner. The control portion of the grid is constituted preferably by the slender wires 17 wrapped helically around the grid supporting rods 16 throughout a large portion of the tube length. We also prefer to have rod 18 preferably of tung-

sten fastened to the central portion of the press 12 and extending axially through the major portion of the tube to provide a suitable filament support. In tubes of the prior art it has been customary to use two V-shaped filaments with the resulting continuous variation in the filament to grid distance which is closest at the ends of the structure and greatest at the mid-point of the filament strands. This variation in distance between the various portions of the filament and the grid and anode structure produces the above-mentioned non-uniform electronic flow along the filament resulting in very undesirable non-uniform heat dissipation in the anode. Accordingly, we have devised the cathode structure to give a uniform distribution of electric current throughout the tube. Our preferred form of filament support is illustrated in the drawing. The two cathode leads 13 and 14 preferably continue through the seal as the sturdy upright rods 19 and 20 on either side of the rod 18. At the point 21, these rods are bent outward to form ends 22 spaced a predetermined distance apart. At the inner end of the rod 18 are attached the hooks 23 and 24 for the free end of the cathode. These hooks are preferably broad metallic structures preferably attached to an insulating quartz tube 42 on the inner end of the filament support rod 18. A U-shaped member 25 with an extension 26 from one of the arms of the U is attached to the rod 18 at a portion adjacent the bend 21 in the rods 19 and 20, as illustrated in the upper portion of Fig. 2. This U-shaped member is preferably of tungsten or molybdenum. The distance between the arms 27 and 28 of the U is the same as that between the ends 22 of the rods 19 and 20. The result is that the arms 27 and 28 of the U-shaped member 25 and the ends of the rods 19 and 20 are spaced equi-distant apart so that they form the corners of the square. Likewise, at the other end of the tube the hooks 23 and 24 have a breadth that is substantially equal to the distance from one hook to the other, and, accordingly, the outer edges of the hooks form the corners of a square similar in size and dimensions to that formed by the arms 27 and 28 and the cathode leads 19 and 20. A filament, preferably of tungsten, is attached to the outer end 22 of the conductor 19 and a portion 39 extends longitudinally of the tube to the hook 23 where it is threaded therethrough and the portion 31 is brought back to the arm 28 of the U-shape member 25. Another filament is attached to the other arm 27 of the U-shaped member 25 and a portion 32 extends longitudinally of the tube through 55

the hook 24 and a portion not disclosed in the drawing extends back to the upper end of the cathode lead 20. The cathode circuit, accordingly, comprises the lead 19, the filament portion 30, 31, the U-shaped member 25, the filament portion 32 and the return portion 33 (see Fig. 3) of the filament to the cathode lead 20.

If it is desired to increase the effective length of the filament without increasing the outside dimensions of the tube, this filament can be waved, as shown in the drawing, to provide a greater emissive area. This structure permits the use of heavier filament wire resulting in longer filament life. This waving may take any desired formation even to that of semi-circles as it is shown in the drawing. It is preferred that the general axis of the wavy filaments be parallel to each other and be symmetrically arranged around the axis of their support.

20 Because of this parallel arrangement of the filament wires and their equal spacing from the grid and anode, there will not be the tendency for concentration of the electron stream at various portions of the tube.

25 We also prefer to have the filaments arranged in symmetrical relation to the grid structure and especially as disclosed in Fig. 3. The grid structure comprises the sturdy support portions 16 with the more slender control portions 17. We desire to locate the filament strands 30 through 33 so that they are in planes substantially bisecting the spaces between the longitudinal wires 16. In this particular arrangement, the electron stream will have a chance to flow from the filament portion to the anode intersected by the slender control portion 17 of the grid and the electrons will not be apt to be absorbed by the large supporting structure 16.

We have likewise discovered that where high voltage is placed on the grid and anode in using these tubes as class B audio operation or as a modulated class C amplifier that sudden discharges are likely to occur at certain spots of the anode, which interrupt the continuous operation 45 of the tube. We have conducted tests on tubes and have found that such flash-overs may occur with a cathode not heated by the heating current and were able to record an instantaneous current as high as 800 amperes. We have discovered that these anode point discharges are prompted by sharp points and edges in tube structure, especially in the supporting means for the upper portion of the filament and free end of the grid structure. We believe that this discharge is caused by the high rate of potential gradient in the neighborhood of the sharp point or edge. Assuming, for instance, that there is an instantaneous difference of say 40,000 volts between the grid and anode or cathode and anode 55 which is not uncommon in water-cooled tubes, and that there is a quarter of an inch between the two, then there would be a potential gradient of the order of 160,000 volts per inch between the two members. The potential gradient would be non-uniform between the two structures if sharp edges or points exist and, at these sharp edges or points, the potential gradient would be many times greater than the value just mentioned. This edge or point, accordingly, would 60 be apt to cause a local discharge between the tube elements and interrupt the smooth operation of the tube.

We have, accordingly, enclosed the outer supporting structure of the filament and grid with metallic shields 35 and 36. The cathode shield 35

may be supported by spot welding or riveting or any other convenient manner at 37 to the inner end of the supporting rod 18 or the hook supporting structure 38 thereon. This cathode shield may take any convenient form, but we prefer to have it of a cylindrical form closed at one end with the cylindrical sides or skirt extending over and enclosing the sharp edges of the hook supports 23 and 24. The grid shield 36 likewise is preferably of a cylindrical form with a closed curved end which may instead be flat if desired, enclosing the free end of the grid structure and the sharp edges of the coil 17 and the supporting rods 16. The edges of the shields 35 and 36 are rounded off so that they do not likewise present any sharp edges. By means of these shields, a localized discharge is prevented between the sharp edges of the upper ends of the cathode and grid structure and of the adjacent portions of the anode. We likewise avoid sharp points, sharp edges and sharp corners throughout the electron discharge area of the tube.

We have also illustrated the band 39 on the tube for the attachment of any suitable cooling jacket thereto and also the seal shield 40 to protect the seal 41.

The structure disclosed in the drawing is to be considered as illustrative of a preferred embodiment of our invention. Various modifications in the elements and their arrangement can obviously be made, and, accordingly, we do not intend our invention to be limited except as is necessitated by the prior art.

We claim as our invention:

1. An electrical discharge device comprising a cathode, anode and grid, said grid having a free end, a supporting hook for said cathode, and metallic shielding means intermediate the free end of said grid and the supporting hook of said cathode.

2. An electrical discharge device comprising an anode, cathode and grid, said cathode and grid supported at one end of said device and having other free ends extending into said anode and metallic shielding means interposed between the other free end of said grid and both the cathode and said anode.

3. Supporting means for a filament cathode comprising a supporting mass, broad hooks attached to opposite sides of said mass, the breadth of said hooks being substantially equal to the distance between adjacent hooks and a shield attached to said mass overlapping said hooks.

4. An electrical discharge device comprising a cathode of a plurality of filaments, a plurality of hooks supporting one of the ends of said cathode, the breadth of said hooks being substantially equivalent to the distance between adjacent hooks, a grid structure surrounding said cathode and an anode surrounding said grid structure, said grid structure comprising sturdy metallic supports and slender control wires, the general axes of said filaments being in planes substantially bisecting the space between said sturdy metallic grid supports.

5. An electrical discharge device comprising a cathode of a plurality of parallel filaments equidistant about a common axis, a plurality of hooks supporting one of the ends of said cathode, the breadth of said hooks being substantially equivalent to the distance between adjacent hooks, a grid structure surrounding said cathode and an anode surrounding said grid structure, said grid structure comprising sturdy metallic supports and slender control wires, the general axes of said filaments being in planes substantially bisecting the space between said sturdy metallic grid supports.

said filaments lying in planes substantially bisecting the space between said sturdy metallic grid supports and a metallic shield enclosing said hooks.

5 6. An electrical discharge device comprising a cathode of a plurality of parallel filaments equidistant about a common axis, a plurality of hooks supporting one of the ends of said cathode, the breadth of said hooks being substantially equivalent to the distance between adjacent hooks, a 10 grid structure surrounding said cathode and an

anode surrounding said grid structure, said grid structure comprising sturdy metallic supports and slender control wires, the general axes of said filaments in planes substantially bisecting the space between said sturdy metallic grid supports, a metallic shield enclosing said hooks and another metallic shield enclosing the adjacent end of said grid structure. 5

ILIA E. MOUROMTSEFF.
